FIG. 1

FIG. 2

FIG. 3

FIG. 4

FIG. 5

FIG. 6

FIGURE 1 is a perspective view of a toaster embodying my new design;

FIGURE 2 is an elevational view of the opposite end of the toaster shown in FIGURE 1;

FIGURE 3 is a bottom view looking up on the toaster shown in FIGURE 1;

FIGURE 4 is a perspective view of a modified form of the toaster shown in FIGURE 1;

FIGURE 5 is an elevational view of the opposite end of the toaster shown in FIGURE 4; and

FIGURE 6 is a bottom view looking up on the toaster shown in FIGURE 4.

The dominant features of the design are shown in solid lines.

The decorative pattern which is partially shown on the

recessed surface of the end plates is understood to cover the entire recessed surface thereof.

I claim:

The ornamental design for a toaster, substantially as above and described.
